UNITED STATES PATENT OFFICE.

ISAAC ARTHUR HILLS, OF GRAND RAPIDS, MICHIGAN.

LUGGAGE CARRIER.

Application filed September 7, 1923. Serial No. 661,372.

To all whom it may concern:

Be it known that I, ISAAC ARTHUR HILLS, a citizen of the United States, and a resident of the city of Grand Rapids, in the 5 county of Kent and State of Michigan, have invented certain new and useful Improvements in a Luggage Carrier; and I hereby declare that the following is a full, clear, and exact description of the same, reference 10 being had to the accompanying drawings, and to the numerals of reference marked thereon, which form a part of this specification.

This invention relates to a combination 15 foot board and luggage carrier for automobiles and the like.

It is an object of this invention to provide in connection with the running board of a vehicle, foot pads which ordinarily 20 serve the usual purpose but which may be swung upwardly into vertical position for retaining luggage upon the running board. It is also contemplated that means extending lengthwise of the running board may be 25 secured to said foot pad for forming a continuous outer barrier upon the foot board for increasing the capacity for carrying luggage.

It is a further object of this invention to 30 provide a novel form of apron plate having provision for attaching luggage, retaining or carrying means.

With these and other advantages in view 35 which will become apparent in the following description and disclosures in the drawing, this invention comprises the novel mechanism and combinations hereinafter described and more particularly pointed out and defined in the appended claims.

40 In the accompanying drawings which illustrate a preferred embodiment of this invention and in which similar reference numerals refer to similar features in the different views.

45 Figure 1 is a fragmentary side perspective view of an automobile illustrating this invention.

Figure 2 is a view similar to Figure 1 showing an outer barrier attached to the 50 foot pads.

Figure 3 is an enlarged fragmentary plan view of the running board of a vehicle with a foot pad attached thereto involving this invention.

Figure 4 is an enlarged fragmentary side 55 elevational view of the running board having this invention applied thereto.

Figure 5 is an enlarged sectional view 60 through the running board taken upon the line 5—5 of Figure 3.

In the illustrated embodiment of this invention, there is shown a portion of an automobile which in the present instance has a pair of doors 1 and 2 and the usual running board 3. A pair of edge plates 4 are 65 bolted to the running board adjacent each door. These plates overlap a portion of the top of the running board and extend down over the outer edge thereof and then horizontally in the form of resilient supporting 70 flanges 5 that afford rests for the lower margins of the luggage carriers when in use. Hinge plates 6 are secured upon the running board in superimposed relation with the plates 4, one of these plates has 75 a tongue-like extension 7 that extends across the running board and forms a support for a latch 8. The outer ends of the hinge plates 6 extend a short distance beyond the running board where they are provided 80 with hinge eyes 9. A foot pad 10 is hinged to each pair of hinge plates 6 by means of the eyes 9. This foot pad is cut away upon the bottom so as to fit over the hinge plates 85 as shown in Figure 5. These cut out portions terminate short of the outer margins of the pads which margins are enlarged and extend a distance beyond the hinge plates substantially equal to the thickness of the running board so that when the pad is 90 swung to a vertical position as shown in dotted line in Figure 5, the enlarged margin will swing against the edge of the running board and the edge of the pad will be forced upon the flange 5 which may yield for this purpose whereby the pad may be retained in such position. The enlarged margin of the pad is preferably provided with a series of 95 dirt removing slots 11. This foot pad may consist of wood, metal, stiff rubber or any suitable rigid material, and the term pad is used to embrace any foot plate or slab for such a purpose.

In the present instances two foot pads 10 are illustrated, one in connection with each door. Either one of these foot pads may be raised into vertical position for carrying luggage or both may be raised if necessary 105

so as to increase the carrying capacity of the running board. It is also possible to removably attach a plate such as illustrated at 12 to one or both foot pads to form a barrier extending substantially the entire length of the running board to further increase the carrying capacity and to prevent the loss of small articles.

In converting the running board into a luggage carrier, it is desirable to protect the side of the vehicle from being scratched or damaged and for this purpose I have shown an apron plate 13 adjacent each foot pad and secured along the inner margin of the running board. Each apron plate may be provided with apertured lugs 14 at its lateral margins for receiving some flexible tying elements for tying or binding luggage upon the running board.

In the utilization of this invention, the pads 10 may normally rest flat upon the running board with the latches 8 engaged thereover to serve as usual foot plates or pads. Where it is desired to carry some luggage such as illustrated by the reference numeral 15 in Figure 1, one of the foot pads may be raised to vertical position as previously explained for retaining such luggage upon the running board. If it is desired to increase the carrying capacity of the running board, the other foot pad may be raised and the barrier plate 12 which can be readily carried in some part of the vehicle may be attached to the elevated foot plates as shown in Figure 2.

From the foregoing it will be apparent that this invention has a two fold utility and that the parts can be readily and quickly converted from one form to the other. It should also be apparent that the novel form of apron plates not only protect the side of the vehicle from the luggage but also afford anchoring means for luggage.

I am aware that many changes may be

made, and numerous details of construction may be varied through a wide range without departing from the principles of this invention, and I therefore do not purpose limiting the patent granted hereon, otherwise than necessitated by the prior art.

I claim as my invention:

1. A luggage carrier, including the running board of a vehicle, pads hinged to the outer margin of said board, and a resilient rest upon the side of said board for releasably sustaining said pads in vertical position.

2. A luggage carrier, comprising the running board of a vehicle, spaced pads hinged to the outer margin of said board, resilient means for retaining said pads in vertical position, and an apron plate extending along the inner margin of said running board and provided with attaching means at its ends.

3. A luggage carrier, including the running board of a vehicle, a pair of foot pads hinged to the outer margin of said board, and resilient means for holding said pads in vertical position.

4. In a vehicle having a running board, a pair of spaced foot pads hinged to the outer margin of said running board, said foot pads having their outer margin enlarged and an angle member providing a rest secured to said running board for receiving and supporting the enlarged margins of said foot pads.

5. In a vehicle having a running board, a foot pad hinged to the outer margin of said running board and swingable from horizontal to vertical position, and means depending over the outer margin of said running board for supporting said foot pad in vertical position.

In testimony whereof I have hereunto subscribed my name.

ISAAC ARTHUR HILLS.
